UNITED STATES PATENT OFFICE.

JOHN W. MCKINNEY, OF SOUTH CHARLESTON, OHIO.

UPSETTING TIRES AND OTHER METALLIC BARS.

SPECIFICATION forming part of Letters Patent No. 241,396, dated May 10, 1881.

Application filed November 12, 1880. (Model.)

To all whom it may concern:

Be it known that I, JOHN W. MCKINNEY, of South Charleston, in the county of Clarke and State of Ohio, have invented a new and useful Improvement in Upsetting Tires and other Bars of Metal, of which the following is a specification.

The invention consists in combining serrated plates, serrated cams, tables, and a wedge-shaped plate, serrated on both sides, as hereinafter described.

In the accompanying drawings, Figure 1 is a top view of a machine embodying my improvements. Fig. 2 is a longitudinal vertical section, taken in the line $x x$ of Fig. 1. Figs. 3 and 4 are detail views.

Similar letters of reference indicate corresponding parts.

The working parts of the apparatus are supported by a base or platform, A, of any suitable construction. On the top of this base or platform rests a stationary table, B, and a movable table, C. The movable table is arranged to slide horizontally on the platform A, and is guided by means of tongues on said platform engaging with grooved ways on said movable table. The stationary table and movable table are both provided with raised sides, in the upper edges of which are bearings b for the journals of rollers D D², the faces of which are grooved for engagement with the tire, in order to prevent lateral vibration thereof while being bent. About midway between these two rollers, but on a higher plane, is a third roller, D³, journaled in standards attached to the stationary table. One of these standards is attached to the raised side of the table by means of a bolt or screw, d³, so that the roller may be readily removed when desired. The roller D³ is provided with longitudinal grooves or serrations, to enable it to engage with the bar to prevent slipping. The bottoms of both the stationary and movable tables are provided with removable plates E, the upper surfaces of which are serrated, for engagement with the lower surface of the tire or bar to be upset. These plates fit snugly in recesses in the tables, so as to prevent their accidental displacement when in use; but they are made removable, in order that they may be replaced by new ones when the serrations become worn.

Immediately over the serrated plates E E

are two cams, G G, the faces of which are serrated like the faces of said plates. The serrations on the cams and the plates run toward the center of the machine. The cams G work on bearings attached to the upright sides of the tables B and C. Each cam is provided with an upright arm or stem, g. The stems g of the two cams are connected by a toggle-joint, h h, with the upper end of a rod, h², the lower end of which is connected to a treadle, H, arranged on one side of the machine.

On the under side of the base or platform is a spring, J, one end of which bears upward against the treadle H, so as to have a tendency to force the faces of the cams upward from the plates E.

Instead of the curved spring here shown, a spiral spring may be arranged in any suitable manner.

To the treadle H is attached the lower end of a bar, K, the upper end of which is widened and bent at a right angle and turned inward at a point immediately over the contiguous edges of the stationary table and movable table. Said horizontal upper portion of said bar K works in, and is guided by, a slot in one of the standards which carry the roller D³.

In the base or platform A is journaled a horizontal shaft, L, one end of which is provided with a handle, l, for turning it, and the other end is provided with a screw-thread. This screw-threaded portion passes through a perforated lug, m, on the under side of the movable table C. This lug may be provided with a screw-thread, or in lieu thereof there may be a nut, n, on each side of the lug, as shown.

The upper surfaces of the tables B and C are inclined downward and inward toward each other and toward the center of the machine, so as to form a concave surface for the bar which is to be upset, after it has been bent to form a tire.

When the bar is to be bent to form a tire it is passed over the rollers D D² and under the roller D³, so as to bend it in the form indicated by the upper dotted lines in Fig. 2, the cams G G having previously been removed. The upsetting is accomplished in the following manner: The rollers D D² D³ are removed and the cams G G are replaced. The tire is passed between the plates E and cams G, and the treadle H is then depressed and held down, so

as to cause the cams G and plates E to bite the bar and hold it firmly between them. The screw-shaft I is then turned so as to draw the movable table C toward the stationary table 5 B. By means of the widened horizontal arm of the bar K the metal is prevented from springing or bulging upward at the point between the tips of the cam.

When a straight bar is to be upset without being bent two auxiliary plates, P, are employed. Each plate is thicker at one end than at the other, and is provided with serrations on the under side for engagement with those on the plate E, and serrations on the upper 15 side running in the same direction as those on the plate E. (See Fig. 4.) The straight bar is passed under the cams G, and its under surface is engaged by a level serrated surface formed by the auxiliary plates, instead of a 20 concave surface, as before described.

The movable table C is provided with a scale, Q, and the stationary table with a pawl, Q², for engagement therewith, by which means the tables B C may be adjusted with relation to each other, in order to regulate the diameter of the tire to be formed. 25

Having thus fully described my invention, I claim as new and desire to secure by Letters Patent—

The combination, with the serrated plates E, 30 serrated cams G G, and the tables B C, of the wedge-shaped plate P, serrated on both sides, as and for the purpose specified.

JOHN WILLIAM MCKINNY.
